UNITED STATES PATENT OFFICE.

ANDREW J. MARTIN, OF MUNCY, PENNSYLVANIA, AND HENRY J. BREESE,
OF MACEDON, NEW YORK.

STOCK-LOADING DEVICE.

SPECIFICATION forming part of Letters Patent No. 376,896, dated January 24, 1888.

Application filed June 3, 1887. Serial No. 240,156. (No model.)

To all whom it may concern:

Be it known that we, ANDREW J. MARTIN, of Muncy, in the county of Lycoming and State of Pennsylvania, and HENRY J. BREESE, of Macedon, in the county of Wayne and State of New York, have invented certain Improvements in Stock-Loading Devices, of which the following is a specification.

The aim of our invention is to provide a simple device by means of which hogs and other small live stock may be conveniently loaded upon cars having an upper and a lower deck; and to this end it consists in an adjustable gangway constructed and combined with operating devices, substantially as herein described.

In the accompanying drawings, Figure 1 represents a side elevation of our device arranged at the side of a railway and adjustable in position for use with a car, which is shown in end elevation adjacent thereto. Fig. 2 represents a cross-section on the line *x x* of Fig. 1.

Referring to the drawings, A represents a railway-car; B, a stationary gangway inclining upward toward the car and terminating at a suitable distance therefrom.

C represents an adjustable section forming a continuation of the gangway, and of proper length to bridge over the space between the car and the stationary section. This movable section consists of a floor portion having at the ends upright posts C and longitudinal side rails, *b*. It is mounted between two stationary side frames, D, these frames consisting of upright posts *c*, connected by suitable side rails or bars. At one end the adjustable section is supported by rollers or journals *a*, seated in or upon the side frames, D, and at the opposite end, adjacent to the car, the movable section is supported by two rack-bars, *f*, jointed thereto and extending downward past pinions *g*, with which they are engaged.

These pinions are secured upon a cross-shaft, *h*, seated in stationary boxes on the side frames and provided at one end with an operating handle or lever, *i*. By turning this handle the adjustable section next to the car may be raised or lowered to the level of the

upper or the lower deck of the car, as required. Pawls *k*, or equivalent locking devices, will be employed to maintain the movable section in its elevated position.

It will be observed that the stationary section is provided with side bars or rails, and that, in connection with the movable section, it forms a continuous passage-way on which the stock may ascend to the car, and from which it is impossible for the stock to escape as they are driven forward, except by passing into the car. The arrangement admits of the section being speedily lowered from the upper to the lower deck, so that the operation of loading the car may be continued without interruption.

We prefer to arrange the operating handle or lever to slide transversely through its head, after the manner of an ordinary vise-handle, that there may be no danger of its projecting in position to encounter the cars.

In order to completely close the space between the end of the movable section when it is elevated and the cars, we may provide adjustable side boards, E, pivoted at their lower ends, as shown at *l*. These may be turned outward and secured by pins *m*, or equivalent devices.

While we have described and shown rack-bars and pinions for elevating one end of the movable section, it is evident that any other suitable means for the purpose may be employed.

We are aware that the end or mouth of a cattle-chute next to a car-track has been hinged and provided with a counter-weight, so that it could be turned upward out of its one operative position away from the track, and also that a fixed chute has been provided with two inclined boards hinged to its side in such manner that they could fold inward to form an inclined platform, and to these constructions we lay no claim.

What we do claim is—

1. In a device for loading live stock, the combination of the stationary inclined gangway, the section forming a continuation thereof, and having one end movable vertically and the other end arranged to move horizontally,

the rack-bars and pinions, and the dogs or locking devices for operating the vertically-movable end of the said section, substantially as described.

5 2. The stationary gangway B, in combination with a vertically-movable section, C, provided with side rails, the pivoted sections E, and the adjusting and supporting devices for the section C, as described and shown.

In testimony whereof we hereunto set our hands, this 23d day of May, 1887, in the presence of two attesting witnesses.

ANDREW J. MARTIN.
HENRY J. BREESE.
